(57) **CLAIM**

We claim the new, original and ornamental design for a razor caddy, as shown and described.

DESCRIPTION

This application is entitled to the benefit of and incorporates by reference essential subject matter disclosed in Design patent application Ser. No. 29/178,709 filed on Mar. 28, 2003.

FIG. 1 is a front perspective view of the razor caddy,

FIG. 2 is a rear perspective view of the razor caddy,

FIG. 3 is a right hand side view of the razor caddy,

FIG. 4 is a front view of the razor caddy,

FIG. 5 is a left hand side view of the razor caddy,

FIG. 6 is a rear view of the razor caddy,

FIG. 7 is a top view of the razor caddy; and,

FIG. 8 is a bottom view of the razor caddy.

The broken-line disclosure in the views is for illustrative purposes only and is understood to form no part of the claimed design.
